Primary Examiner — T Chase Nelson(74) Attorney, Agent, or Firm — Shook Hardy & Bacon, LLP(57) CLAIM

The ornamental design for a shoe, as shown and described.

DESCRIPTION

FIG. 1 is a bottom plan view of a shoe showing my design; FIG. 2 is a bottom first side perspective view thereof; and, FIG. 3 is a bottom second side perspective view thereof. The even-length broken lines are directed to environment, represent unclaimed subject matter, and form no part of the claimed design. The long and short broken lines surround not only the outer perimeter of the claimed subject matter, but also surround unclaimed subject matter within the claimed, shaded areas. These long and short broken lines form unclaimed boundaries between claimed subject matter and unclaimed subject matter and form no part of the claimed design.
